UNITED STATES PATENT OFFICE.

THEODORE L. FOUST, OF TERRE HAUTE, INDIANA.

INVALID-BED.

1,317,694.

Specification of Letters Patent.

Patented Oct. 7, 1919.

Application filed April 12, 1917. Serial No. 161,558.

To all whom it may concern:

Be it known that I, THEODORE L. FOUST, a citizen of the United States, residing at Terre Haute, in the county of Vigo and State of Indiana, have invented a new and useful Invalid-Bed, (Case A,) of which the following is a specification.

This invention relates to invalid beds and is more particularly designed as an improvement upon the structure disclosed in Patent No. 1,197,731, issued to me on September 12, 1916.

One of the objects of the invention is to provide a sectional mattress of novel form, whereby either of the legs of the occupant of the bed can be raised or lowered by manipulating certain of the mattress sections, and whereby the upper portion of the body can likewise be raised or lowered as desired.

Another object is to provide mattress sections of novel form and which are carried by frames which are simple and durable in construction.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings:

Figure 1 is a side elevation of a bed embodying the present improvements.

Fig. 2 is a plan view thereof, the posts being shown in section.

Fig. 3 is a central vertical section.

Fig. 4 is a section on line 4-4 Fig. 1.

Referring to the figures by characters of reference 1 and 2 designate the end frames of the bed, these frames being connected at one side by a continuous rail 3 and at the other side by a rail 4 having, between its ends, a depending yoke 5 integral therewith.

Cross strips 6 connect the upper ends of the sides of the yoke 5 with the opposite rail 3 and mounted for vertical movement between these strips 6 is a holder 7 designed

to support a small mattress section in the form of a plug 8. Any suitable means may

be employed for raising and lowering the holder but as this holder and its operating means constitutes no part of the present invention, it is not deemed necessary to describe or illustrate the same in detail.

Extending upwardly from the end portions of each of the strips 6 are short standards 9 and 10 respectively. Upper side rails 11 are secured at their ends to the standards 60 9 and 10 and constitute the sides of the middle mattress section. These rails 11 are preferably angle strips with their flanges extending inwardly toward each other and extending inwardly from these flanges are 65 coiled springs 12 attached to the ends of transversely extending flexible strips 13 preferably of spring metal. Spring strips or wires 14 are fastened at their ends to the strips 13 and are preferably parallel, the 70 innermost strips 14 being spaced apart to form a large opening directly over the holder 7. One of the strips 13 can be cut out as shown at 15 so as to increase the size 75 of this opening.

Hingedly connected to the standards 9 are angle strips 16 forming the sides of the frame of the head portion of the mattress, these side strips being connected at their free ends by an end strip 17. Extending 80 from the side strips close to their pivots 18 are coiled springs 19 which are attached to the ends of a flexible strip 20 preferably of metal and which strip is close to and parallel with one of the strips 13. The two 85 strips 20 and 13 are preferably connected by small rings or loops 21.

Connecting the side angle strips 16 close to their pivots is a cross bar 22 supported throughout the greater portion of its length 90 below the side bars or strips 16, the ends of this cross bar being bent upwardly and fastened to the side bars 16, as shown particularly at 22' in Fig. 3. A pair of additional cross bars 23 connects the side bars 16 100 near the end bar 17 and these cross bars 23 are secured to a block 24 located preferably adjacent the centers thereof and which is pivotally engaged by the upper end of an arcuate rack bar 25.

Cross bars 26 connect the side rails 3 and 4 and are provided thereunder with trusses 27 including central spacing blocks 28. These spacing blocks may be made integral, they being provided with connecting webs 110 29 in which is journaled a transverse shaft 30 to which is secured a gear 31. This gear

constantly meshes with the rack 25. Shaft 30 can be rotated in any suitable manner, as by means of a crank arm 32 and a ratchet wheel 33 may be secured to this shaft, this 5 ratchet wheel being normally engaged by a pawl 34 whereby rotation of the shaft in one direction will be prevented. In other words, by rotating the shaft 30 in one direction so that the ratchet will slip under the pawl 10 34, the rack 25 will be moved upwardly and cause the mattress frame made up of the bars 16 and 17 and their connections to swing upwardly about their pivotal connections with the standards 9. Reverse or 15 downward movement of the parts is prevented, however, unless the pawl 34 is disengaged from the ratchet wheel.

A wire fabric indicated generally at 35 is connected to the bars 16 and 17 and to the 20 flexible strip 22 and this fabric is adapted to support a tufted mattress section 36 which can be connected in any suitable manner to another tufted mattress section 37 which rests on the strips 13 and connections 14 as 25 well as the side rails 11, this section 37 having an opening 38 therein designed to receive the plug 8 when the holder 7 is elevated.

Extending upwardly from the middle 30 portion of the cross strip 6 on which the standards 10 are mounted are intermediate standards 39 similar to the standards 10. Pivottally attached to each standard 10 and to the adjacent standards 39 is a U-shaped 35 frame 40 preferably offset downwardly near the pivot end thereof as shown at 41. Each of these U-shaped frames has an inwardly extending flange along the sides and end thereof as indicated at 42 and secured on 40 these flanges are cross strips 43.

Rings or loops 44 are extended from the longitudinal edge of the strip 13 and pivotally mounted in these rings is the upper frame 45 of a spring mattress section. This 45 section also has a lower frame 46 adapted to rest on the strips 43, the two frames 45 and 46 being connected by springs 47. A tufted mattress section 48 is adapted to rest on the frame 45 and the springs connected 50 thereto.

It is of course to be understood that one of these mattress sections is arranged above each of the frames 40.

Secured to the middle portion of the free 55 end of each of the frames 40 is a cord or light cable 49 extending upwardly and fastened to a shaft 50 journaled in bearings 51. The two shafts 50 are preferably in alinement although capable of independent 60 rotation and each shaft has a ratchet wheel 52 adapted to be engaged by a pawl 53 so as to prevent the cable from unwinding from the shaft. Any suitable means such as a crank arm 54 may be provided for rotating 65 each of the shafts. The parts are

so arranged that when the shaft is rotated in one direction the cable 49 will be wound thereon and the pawl and its ratchet will hold the shaft against rotating in the opposite direction. This rotation will result 70 in the elevation of the mattress section to which the cable is attached. By loosening the pawl 53 out of engagement with its ratchet wheel, said section can be lowered to a horizontal position or past the horizontal. 75

A bracket 55 can be attached to one of the side rails of the bed and is adapted to hold a standard 56. This standard can be raised to a desired elevation and then held 80 by means of a set screw 57. An arm 58 extends radially from the upper end of the standard and a table section 59 may be adjustably mounted on this arm.

It will be apparent that by providing a 85 mattress section such as described, all of the sections can be adjusted until they are perfectly horizontal, the back of the patient resting on the mattress section 36, while the legs rest upon the respective mattress sections 48. By rotating shaft 30 as described, the back portion can be raised to a desired angle and, by means of the shaft 50 and the parts connected thereto, the respective leg sections can be adjusted upwardly or downwardly as desired. 90

The construction of the various sections is simple, durable and efficient and the parts are so assembled that they will not readily get misplaced or out of order. 100

What is claimed is:

1. The combination with a supporting structure, of upper side rails, a frame hingedly connected to said rails at one end, and carrying a bed fabric constituting the head portion of the bed, a flexible strip secured to the hinge end portion of said fabric and yieldingly connected at its ends to the frame of said head portion, separate hinged frames connected to the other ends 105 of said rails and extending downwardly and forwardly therefrom, separate means for raising and lowering the respective frames at the two ends of the rail, parallel cross strips yieldingly connected at their ends to 110 the ends of the rails, spring wires connecting said cross strips, loops connecting one of said cross strips to the flexible strip of the said bed fabric, springs mattress sections carried by the separate hinged frames 115 forming one end of the bed, each section including an upper frame and ring connections between said upper frames and one of the cross strips.

2. An invalid bed including upper side 120 rails, a head portion hingedly connected to one end of the side rails and carrying a spring fabric, separate leg portions hingedly connected to the other end of the rails and each including a frame, spring mattress sections 125

resting on the respective frames and having upper frames, yieldingly supported cross strips connected at their end to the side rails, rings connecting the upper frames 5 of the leg portions to one of the cross strips, rings connecting the spring fabric of the head portion to the other said cross strip, springs connecting between the cross strips, and separate means for raising and lower-

ing the head and leg portions respectively 10 of the bed.

In testimony that I claim the foregoing as my own, I have hereto affixed my signature in the presence of two witnesses.

THEODORE L. FOUST.
